UNITED STATES PATENT OFFICE.

HUGO JUNGK, OF ERFURT, GERMANY.

SHEET-FEEDING MACHINE.

Application filed October 25, 1928, Serial No. 144,017, and in Germany October 28, 1925.

With ruling machines and the like the sheets of paper are withdrawn, as is known, from a pile supported upon a stationary table by means of a withdrawing device, and are then introduced into the respective machine. The withdrawing device is formed generally by a two-wheeled carriage composed of a bow provided with two wheels having rubber tyres, that carriage being reciprocated upon that sheet which is the uppermost of the pile at the time being, its to-and-from movement being effected by a connecting rod. The said wheels are provided with a checking device preventing them from rotation when the carriage is drawn towards the machine the adhesion of the rubber tyres on the uppermost sheet of paper withdrawing this sheet from the pile and conveying it to the conveying threads of the respective machine (ruling machine or the like). In order to prevent that more than one sheet is withdrawn from the pile, there are provided at the rear edge of the pile small knives or needles attached loosely to vertical rods and bearing with their pointed ends upon the pile and piercing through the uppermost sheet because they are subjected to the pressure of a suitably arranged weight. The uppermost sheet which is to be withdrawn by the above-mentioned carriage with the aid of the adhesion, as stated, must, therefore, be torn away from said knives or needles, and this being so there remain fibres, as well as scraps, of paper that are carried into the ruling machine and impair its operation, especially the product. The fibres and scraps adhere chiefly to the ruling rolls whereby the ruling lines produced by these rolls are more or less severely impaired. Besides, as the sheets have been torn off the knives or needles, it becomes necessary to cut the respective rims or edges. If the sheets have been cut to the proper size already before the ruling they must be introduced manually into the machine; they cannot be introduced automatically.

The object of the present invention is to obviate the drawback disclosed at the end of the preceding paragraph, and I attain that object by an improved method consisting in vaulting the uppermost sheet at its rear rim, the next sheet being thereby so much exposed, that a pressing member can be brought to bear on it, this member retaining the remaining sheets when the said carriage

is drawn towards the machine together with the uppermost sheet.

The invention is carried into practice by the device illustrated diagrammatically and by way of example on the accompanying drawings in Figs. 2-8, whereas Figure 1 shows the old device in which knives or needles are employed; Figure 2 is a side view of a low pile of sheets, together with some adjacent members, and shows the uppermost sheet vaulted according to the present invention; Figure 3 is a plan of the parts shown in Fig. 2; Figure 4 is a front view of a device for effecting the vaulting in question; Figure 5 is a plan of this device; Figure 6 shows it from the left, and Figure 7 shows it from the right, all as fully described hereinafter. Fig. 8 is a cross section on the line VIII—VIII in Fig. 4 the vaulting member being swung into the other position and lifted off. The pile of paper 1 is supported upon a stationary table 5. The two-wheeled sheet withdrawing carriage 2 is moved rearwardly and forwardly upon that pile. When the carriage is moved to the right (Figs. 1 and 2), its wheels roll freely over the paper; when it is moved to the left, the wheels are checked and pull the uppermost sheet of paper with it, as already explained in the introductory part of this specification. While the carriage is moved to the right, the uppermost sheet is vaulted by a suitably formed and actuated member 6, and as the rear edge of the sheet is shifted to the left thereby, the righthand rim of the next sheet is exposed and a pressing member 7 is lowered down upon that sheet whereby the pile is retained.

There may be formed either only a partial vault, as in Fig. 3, or a complete vault by the use of two members 6, one on one side, the other on the other side of the sheet. The vault may be formed by a merely mechanically acting member like 6, whereby merely friction or adhesion, or friction and adhesion will be active, or the member 6 or any other member may be so designed as to be able to effect a sucking action in order to make the sheet adhere sufficiently strongly to it. If a vault or vaults shall be formed only at the corners of the sheet, the shifting member 6 or its equivalent can be moved, besides parallel to the carriage, also obliquely or even at right angles, thereto. An undesired shifting of the entire sheet, without forma-

tion of a vault or vaults, need not be feared because the sheet is held fast by the carriage. Anyhow, a special retaining finger, for instance as 8, Fig. 3, may be used by way of 5 precaution as regards a possible shifting of the entire sheet. The finger 8 presses upon the sheet while the member 6 forms the vault, but is lifted off the sheet immediately before the carriage moves to the left. Moving 10 the member 6 back into its initial position after the vaulting of the paper must be effected, of course, in such a manner that it does not come in contact with the paper and displaces it.

15 Before proceeding I refer briefly to Fig. 1 in order to make clear the difference between the improved method disclosed in the preceding two paragraphs, and the old one. In Fig. 1, 1 denotes the pile, 2 the carriage, 3 the needle (there are, in fact, two needles, although only one is visible in the figure), and 4 the rods to which the needles, which are suitably weighted, are attached. The manner of operation of this device has 20 been described already in the paragraph, following immediately the preamble to this specification.

It is obvious that a variety of mechanisms 30 may be designed to move the shifting or vaulting member 6 or its equivalent in the required member. An example of one of the many possible constructional forms is shown in Figs. 4-8 in which 9 denotes a casting shoved loosely upon two vertical rods 11 affixed to the pile table 10. The casting 9 has vertical bores in which bolts 12 and 13 are movable and subjected to the pressure of helical springs enclosed in 35 said bores above said bolts. The upper portion of the casting 9 forms two bearings 14 supporting a horizontal shaft 15. The bores mentioned are so located in the casing with respect to the shaft 15 that one lies on one side, the other on the other side of the 40 same.

The shaft 15 carries two fingers 16 which are firmly affixed to it, curved, and extend into the upper ends of the said bores where they bear upon the upper ends of the said 45 bolts. To one of the ends of the shaft 15 is secured an obliquely upwards extending arm 18, and the other shaft end is connected with the sheet shifting or vaulting device described hereinafter. The arm 18 is swung 50 to and fro by a connecting rod 19, and the bolts 12 and 13 are alternately lifted and lowered, that is to say, lifted off the sheet of paper and pressed down upon it, the lifting being effected by the respective 55 spring which had been compressed by the vertical movement of the respective finger 16. The lower end of each bolt is provided with a rubber foot. After the one or 60 the other bolt has been depressed, it is checked by a spring-actuated slide-bolt 22.

Each of these slide-bolts has a bore through which the respective pressing bolt 12 or 65 13 extends when being in its upper position. If the respective pressing bolt has, however, been depressed, the appertaining slide-bolt is shifted by the spring appertaining to 70 it so that its bore is then located eccentrically to the bore in which the respective pressing bolt is guided whereby this latter is checked. The checking is maintained until 75 a lug 16^a, or 17^a respectively, made integral with the finger 16, or 17 respectively, contacts with the respective slide-bolt and shifts it back into its initial position, whereby the respective pressing bolt is released and is 80 lifted by the appertaining spring.

While the shaft 15 is turned in that direction in which the arm 18 is moved towards the pile, the bolt 13 is moved away from this latter, and when the arm 18 moves 85 in the other direction, the bolt 12 is moved away from the pile. The weight of the device is carried, therefore, alternately by the bolt 12 and the bolt 13.

Concerning now the vault-forming device, this consists of an oscillating link 23 and the vaulting member proper 24/24^a, the member 24 being curved, as shown in Fig. 7, and the member 24^a consisting of rubber and having wedge-like shape, also as shown. 90 The link 23 encloses a block 25 located upon an overhanging end of the shaft 15. The link 23 and the vaulting member 24/24^a are connected with each other by a spindle 26 extending through the entire height of the link and the block, and having at its lower end a thread upon which the member 24 is 95 screwed, whereas the upper end is provided with a grip 26^a. That portion of the spindle 26 located between the lower face of 100 said block and the opposite inner face of the link is encompassed by a helical spring 26^b which constantly tends to press the link downwards. In the lowermost position of 105 the link the rubber foot 24^a bears upon the pile, i. e. upon the uppermost sheet of the 110 same, but it is never loaded with the weight of the casting 9 with its appertaining parts.

The spindle 26 can be turned by means of the grip 26^a whereby the pressure with which 115 the vaulting member 24/24^a presses upon the paper can be varied. In order to prevent the vaulting member from turning when the spindle is turned, it is vertically guided by two pins 27 extending down from the link 120 23 into bores provided in the said vaulting member.

The manner of action of the vaulting member with respect to the uppermost sheet 125 of paper of the pile is accurately that described with respect to the member 6 in Figs. 2 and 3. When it is moved to the left (Fig. 7), it produces a vault in said sheet or, more precisely, in a corner of the same, the main portion of the paper being held 130

fast by the pressing bolt 12; when the right-hand rim of the paper has been shifted to the left, the pressing bolt 13 contacts with the righthand rim of the sheet below and holds that entire sheet fast while the uppermost sheet is withdrawn by the withdrawing carriage 2 (Figs. 2 and 3). Prior to this withdrawing the vaulting member is lifted a little which is effected by means of a roll 28 that is attached to the link 23 at a side of the same and runs along upon a curved projection, 9^a of the casting 9. It is suited to the purpose to attach the roll 28 not directly to the link 23 but to a check 28^a adjustable at the link whereby it is rendered possible to lift the vaulting member 24/24^a a little earlier or a little later after the formation of the vault in the paper.

The vaulted member is locked in its lifted position by a spring-actuating lever 29 which is provided with a rest 29^a and sits loosely upon the shaft 15, the spring 29^b which actuates said lever being connected at one end with the same and at the other end with the link 23, and the said lever engaging in the proper moment a pin 30 projecting forth from the said link. When the vaulting member swings back into its initial position it or, more precisely, its rubber foot (24^a) is remote from the pile, i. e. a little above it. The lever 29 takes part in the swinging movement, but near the end of its backward movement it is retained by an adjusting screw 31 carried by an arm 32 hinged to the casting 9. Owing to the lever 29 being retained by said arm and screw in the proper moment, the pin 30 leaves the rest 29^a so that the vaulting member is depressed by the spring 26^b and its rubber foot contacts again with the paper. If the arm 32 is turned to the side so that the screw 31 is withdrawn from the path of the lever 29 the vaulting member remains lifted and swings to and fro without touching the paper.

33 is a hook which is hinged to the casting 9 and by means of which the entire vaulting device can be attached to the upper end of one of the rods 11 after having been shifted upwardly along them.

Finally, I wish it to be understood that instead of the purely mechanically acting vaulting member 24/24^a a so-called suction head may be employed which makes the paper adhere to it by suction.

I claim:

1. In a sheet feeding machine, the combination of a paper-table, with front feeding devices, a twin-socket loosely mounted upon vertical rods of said paper-table, two spaced spring-actuated stamp-like pressing fingers vertically shiftable in bores provided within said socket, a stroking buckler rotatably mounted on said twin socket, and means for alternately moving up and down said press-

ing fingers so as to alternately carry said twin-socket.

2. A sheet feeding machine, as specified by claim 1, wherein a spring-actuated arm is hinged to the twin-socket, said arm carrying at its lower end a curved vaulting member provided with a rubber foot adapted to engage the upper sheet of a pile of paper placed on the paper-table.

3. A sheet feeding machine as specified by claim 1, having a shaft carried by the twin-socket, an arm adapted to rock said shaft, a rod operatively connected to the driving gear for said machine, said shaft being provided at one of its ends with a sector-shaped member and cams for alternately depressing the pressing fingers, slide bolts for checking the motion of said pressing fingers when in depressed condition, and a projection for releasing the respective bolts after having effected the pressing action of said fingers.

4. A sheet feeding machine as specified by claim 1, having a rocking shaft carried by the twin-socket, an arm adapted to rock said shaft, a rod operatively connected to the driving gear for said machine, said rocking shaft bearing at one of its ends a sector-shaped member and being provided with cams for alternately depressing the pressing fingers, slide bolts for checking the motion of said pressing fingers when in depressed condition, a projection for releasing the respective bolts after effected pressing action of said fingers, springs for actuating said slide bolts, and a bore provided on said slide bolts, said bore serving for the passage of the respective pressing finger.

5. A sheet feeding machine as specified by claim 1, having a rocking shaft carried by the twin-socket and adapted to be rocked by an arm, a rod operatively connected to the driving gear for said machine, said rocking shaft bearing at one of its ends a sector-shaped member and being provided with cams for alternately depressing the pressing fingers, slide bolts for checking the motion of said pressing fingers when in depressed condition, and a projection for releasing the respective bolts after effected pressing action of said fingers, said sector-shaped member forming a link and enclosing a block attached to one end of said shaft, and a spring tending to move said link back into its normal position after every actuation.

6. A sheet feeding machine as specified by claim 1, having a rocking shaft carried by the twin-socket, a spring-actuated arm adapted to rock said shaft, a rod adapted to be operated by the driving gear for said machine, said rocking shaft bearing at one of its ends a sector-shaped member and being provided with cams for alternately depressing the pressing fingers, slide bolts for

checking the motion of said pressing fingers when in depressed condition, a projection for releasing the respective bolts after effected pressing action of said fingers, said 5 spring-actuated arm carrying a roller contacting with the upper surface of the twin-socket near the end of the stroking movement, a member adapted to withdraw and lock said arm and to be pressed back at the 10 end of the idle back stroke, and an adjusting screw contacting therewith.

7. A sheet feeding machine as specified by claim 1, having a rocking shaft carried by the twin-socket, a spring-actuated arm 15 adapted to rock said shaft, a rod adapted to be operated by the driving gear for said machine, said rocking shaft bearing at one of its ends a sector-shaped member and being provided with cams for alternately depressing 20 the pressing fingers, slide bolts for checking the motion of said pressing fingers when in depressed condition, a projection for releasing the respective bolts after effected pressing action of said fingers, said 25 spring-actuated arm carrying a roller adjustably mounted thereon and contacting with the upper surface of the twin-socket near the end of the stroking movement, a member adapted to withdraw and lock said arm

and to be pressed back at the end of the 30 idle back stroke, and an adjusting screw contacting therewith.

8. A sheet feeding machine as specified by claim 1, having a rocking shaft carried by the twin-socket, a spring-actuated arm 35 adapted to rock said shaft, a rod adapted to be operated by the driving gear for said machine, said rocking shaft bearing at one of its ends a sector-shaped member and being provided with cams for alternately de- 40 pressing the pressing fingers, slide bolts for checking the motion of said pressing fingers when in depressed condition, a projection for releasing the respective bolts after effected pressing action of said fingers, said 45 spring-actuated arm carrying a roller contacting with the upper surface of the twin-socket near the end of the stroking movement, a member adapted to withdraw and lock said arm, and to be pressed back at the 50 end of the idle back stroke, and an adjusting screw contacting therewith, said arm consisting of two parts which are adjustable with respect to each other so as to vary the pressure of the stroking buckler upon the 55 pile of paper placed on the paper-table.

In testimony whereof I affix my signature.
HUGO JUNGK.
